United States Patent Office

Des. 224,664

Patented Aug. 22, 1972

224,664

COPYING MACHINE

Georges Louis Joseph Peynet, 59 Rue Lamarck,
Paris 18, France

Filed Sept. 1, 1970, Ser. No. 24,794

Claims priority, application France Mar. 19, 1970

Term of patent 14 years

Int. Cl. D16—03

U.S. Cl. D61—1

FIG.1

FIG.2

FIG.3

FIG.4

FIG.5

FIG. 1 is a right side perspective view of a copying machine showing my new design.

FIG. 2 is a rear-top perspective view thereof.

FIG. 3 is a top plan view thereof.

FIG. 4 is a rear elevational view thereof.

FIG. 5 is a front elevational view thereof.

The bottom of my copying machine is plain having no ornamental features whatsoever.

I claim:

The ornamental design for a copying machine, substantially as shown and described.
